UNITED STATES PATENT OFFICE.

AUGUST J. KREUZKAMP, OF BROOKLYN, NEW YORK, ASSIGNOR TO ENGLANDER
SPRING BED COMPANY, OF BROOKLYN, NEW YORK.

BED-SPRING.

1,297,697.

Specification of Letters Patent. Patented Mar. 18, 1919.

Application filed October 20, 1914. Serial No. 867,570.

To all whom it may concern:

Be it known that I, AUGUST J. KREUZKAMP, a citizen of the United States, residing at Brooklyn, in the county of Kings and 5 State of New York, have invented certain new and useful Improvements in Bed-Springs, of which the following is a specification.

This invention relates to bed springs, more 10 particularly to that form thereof known as spiral bed springs, in which the spring consists of suitable supporting means and spiral springs carried thereby for supporting the ordinary stuffed mattress, the object of the 15 invention being to provide an improved spring of this kind.

Heretofore it has been found practicable to provide only flat bed springs, that is 20 springs in which the bottom is formed of a fabric of some kind, with side-guards, and although it has been highly desirable to make spiral bed springs with side-guards this has not been found practicable for 25 various reasons, among others the difficulty of attaching and the difficulty of maintaining such side-guards in shape and position, and therefore I believe that I am the first to provide a side-guard spiral bed spring in which the guards will prevent the shifting, spreading, 30 and flattening of a stuffed mattress and maintain it in its boxlike shape, and therefore the object of the present improvement is the provision of a bed spring of the class described having side-guards which are inexpensive but practically applied, and 35 which structure is durable and practicable so that all the advantages of the ordinary side-guard flat spring are obtained in the spiral form of bed spring.

40 In the drawings accompanying and forming part of this specification, Figure 1 is a perspective view of this improved spring; Fig. 2 is a side view thereof; and Fig. 3 is a detail view of the guard partly broken away.

45 Similar characters of reference indicate corresponding parts throughout the several figures of the drawings.

The spiral spring supporting means may consist of any suitable framework 2. In 50 the form shown it consists of a pair of longitudinal extending bars 3 shown as of angle

iron form connected crosswise at their ends by suitable angle iron bars 4, and by a series of intermediate bars. Supported by these bars are a series of spiral springs 5 of any suitable form. The outer row of springs at each side of the bed spring is shown connected by a longitudinally extending wire or rod 6 inturned at its ends as at 7 and connected along the inner sides of certain 60 of the springs. The angle iron bars 4 are bent upward at their ends as at 8 so as to extend above the spiral springs a predetermined distance, thus forming guard supporting means or brackets 8', and these 65 brackets are connected by braces 9 with the spring supporting means, and the upturned portions are also suitably braced. In the present instance the lower ends of the braces 9 at each side of the bed spring are connected with the outer longitudinal extending 70 bar. Stretched between the upper ends of the supporting brackets is a suitable side guard 10. In the present instance this guard is formed of fabric, as for instance a 75 woven wire fabric, and in this form of guard each end thereof is provided with a binding strip 11 and each end is secured by one or more, shown as three in number, coil springs 12 with a bracket 8' whereby the guard is 80 maintained under tension so that it will normally retain its upright position and be returned to its normal position when flexed therefrom. In the present instance each guard is provided with a large or reinforced 85 upper edge 13 which, in the form shown, consists of a series of spirally wound wires effective also to assist in maintaining the side-guard under tension. The lower edge 90 of the guard is preferably provided with a longitudinally extending wire 14 thereby reinforcing it, and it is tied at intervals by metal rings to the spiral spring connecting wire 6 whereby the guard will move to a certain extent with the spiral springs when 95 these are compressed, while at the same time the guard will also assist the springs in maintaining their normal position and thus resist any compressive force applied thereto.

100 It will be observed that in the present improved structure the supporting brackets extend above the spiral springs so that the

guard of whatever form may be used is located above the tops of whatever forms of spiral springs that may be used, so that when the stuffed mattress is in position the 5 guard will always be in proper position to prevent any shifting and flattening and spreading of the stuffed mattress, and maintain it in its box-like form.

In practice the height of the guard member 10 may be varied somewhat, but it is usually about three inches high, and therefore extends about this distance above the spiral springs. In other words, by reason of the present construction any compression of 15 the side row of spiral supporting springs carries with them the side-guards which, however, by reason of the fact that these side-guards are supported under tension, is maintained in proper position to insure the 20 advantages referred to.

It will be understood that the various details may be more or less modified without departing from the spirit or scope of the present improvement, which broadly consists in the provision of means located above the spiral supporting springs for maintaining the shape of the stuffed mattress and preventing the spreading and flattening and shifting thereof. For instance, it will 25 be understood that the supporting means as used herein and in the claims may consist of any means which supports or connects or ties the several springs into a structure whereby it may be utilized as a spring mattress. 30

The spiral bed springs as frequently called, are not infrequently called box springs by reason of the fact that the structure is usually covered with some suitable 35 form of ticking, that is to say, the springs are usually entirely inclosed along the sides, ends and top with ticking, while the bottom is usually of some cheaper material and, of course, when the spring is so covered the 40 guards could likewise be covered by the ticking also. Of course, it will be understood that the spring structure itself may be so covered without covering the side-guards if this is not desired.

50 I claim as my invention:

1. A bed spring comprising supporting means, a series of spiral springs carried thereby, brackets at each side extending above said springs, a guard member connected to said brackets for preventing a 55 stuffed mattress from flattening, spreading and sagging over the lengthwise edge of the spring, and means connecting said guard member with the outer row of springs, said means consisting of a longitudinally extending wire tied to said springs and a longitudinally extending wire connected with the bottom of said guard member, and means connecting said wires. 60

2. A bed spring comprising supporting 65 means, a series of spiral springs carried thereby, said supporting means including a pair of cross members having upturned bracket portions extending above said spiral springs at the corners of the bed spring, a 70 side-guard stretched under tension between said brackets and extending above said spiral springs for preventing a stuffed mattress from flattening, spreading and sagging over the edge of the spring, and braces connecting said upstanding brackets with the 75 spiral spring supporting means.

3. A bed spring comprising rigid supporting means including crosswise connecting members at the ends thereof, each of 80 said connecting members having at its ends upstanding brackets, a guard member extending along each longitudinal edge of the spring and stretched under tension between said brackets for preventing a stuffed mattress from flattening, spreading and sagging over the edge of the spring, spiral 85 springs carried by said rigid supporting means, each outer row thereof having their upper ends terminating adjacent to the bottom of a guard member, and means connecting the bottom of the guard member with said spiral springs, said means comprising a longitudinally extending wire tied to said springs and to the bottom of said guard 90 member. 95

4. A bed spring comprising rigid supporting means including crosswise connecting members at the ends thereof, each of 100 said connecting members having at its ends upstanding brackets, a guard member extending along each longitudinal edge of the spring and stretched under tension between 105 said brackets for preventing a stuffed mattress from flattening, spreading and sagging over the edge of the spring, spiral springs carried by said rigid supporting means, each outer row thereof having their upper ends terminating adjacent to the bottom of a guard member, means connecting 110 the bottom of the guard members with said spiral springs, said means comprising a plurality of longitudinally extending wires connected to said springs and to the bottom of said guard member, and means for imparting additional tension to said guard member. 115

5. A box bed spring including spiral supporting springs, guards carried by said springs and stretched under tension along 120 a plurality of the edges of said box spring and each connected directly with an outer row of said spiral springs, and means for imparting additional tension to each of said guards for preventing a stuffed mattress 125 from flattening, spreading and sagging over the edge of the spring.

6. A box bed spring including spiral sup-

porting springs, woven metal fabric side
guards directly carried by said spiral
springs and stretched lengthwise under ten-
sion from end to end lengthwise of such
5 box spring, and means for imparting addi-
tional tension to each of said side guards,
for preventing a stuffed mattress from flat-

tening, spreading and sagging over the edge
of the spring.

AUGUST J. KREUZKAMP.
